UNITED STATES PATENT OFFICE

LLOYD G. COPEMAN, OF FLINT, MICHIGAN, ASSIGNEE TO COPEMAN LABORATORIES COMPANY, OF FLINT, MICHIGAN, A CORPORATION OF MICHIGAN

CLOTHESPIN

Application filed May 5, 1930. Serial No. 449,834.

This invention relates to clothes pins, and pertains particularly to permanent non-breakable clothes pins.

The standard wood clothes pin is open to many objections including splintering, easy breakage, discoloring and tearing of the clothes. Wooden clothes pins having resiliently mounted relatively movable clamping members have practically the same disadvantages except that it is possible to obtain a much firmer grip upon the clothes. It has also been proposed to mold clothes pins and give the same such shape as to tend to prevent rupturing at the bight.

It is the object of the present invention to provide a clothes pin which embodies the advantages of a spring pressed wood clothes pin without any of its disadvantages and which also gives better results than a divided wood clothes pin in that it is integral, is permanent so as to last indefinitely, is of such material that it will never injure the clothes and will readily give when necessary.

More specifically, the present invention embodies the use of molded rubber in the fabrication of a novel clothes pin. The advantages of such a clothes pin include leg portions or tongues which resiliently grasp the clothes without forcing and without tearing of the clothes. Other advantages include the novel results obtained because of the material of the clothes pin as compared to wood or other non-elastic material.

In the drawing:

Fig. 1 is an elevation of one form of clothes pin embodying the present invention.

Fig. 2 is a modification similar to Fig. 1 with the exception that the pin is formed of two parts molded together.

Fig. 3 illustrates a further modification in that additional spring means are embodied as an integral part of the rubber pin.

Fig. 4 shows a further embodiment of the invention and illustrates the wide adaptability of rubber in the forming of a clothes pin.

Fig. 5 is a section taken on line 5—5 of Fig. 1.

Fig. 6 is a section taken on line 6—6 of Fig. 3.

One of the essential features of the present invention is that the clothes pin, whatever may be its molded form, consists mainly of rubber. The consistency of such rubber may obviously vary considerably and still accomplish the main results as hereinafter set forth. One of the main features of the invention is the obtaining of an improved resilient grasping action of the legs or tongue members at a point adjacent the mouth of the pin.

In Fig. 1 I accomplish this result by molding an integral clothes pin 1 having integral members or tongues 2 which, preferably converge as at 3 to form a grasping point and which diverge as at 4 to form a suitable mouth for receiving the clothes and the clothes line. In molding this integral article the tongues 2 are preferably shaped as to touch or substantially touch at the point 3. In addition to the peculiar shape of the leg members, the resiliency at the point 3 is preferably maintained by the forming of suitable reinforcing ribs 5. These ribs 5 are adapted to resiliently resist outward movement of the leg members 3. In addition to the space 6, an enlarged aperture 7 is preferably formed at the juncture of the legs so as to make room for the clothes line or wire.

The rubber material forming the clothes pin is preferably elastic so that in addition to the normal resiliency of the leg members the surface of the pin itself is adapted to give slightly so as to provide an extremely efficient grip for all types of clothes from sheer thin stockings to the heaviest of materials.

In order to more positively obtain resiliency of the leg members at the point 3 the clothes pin may be formed in two separate halves so that when the two halves are brought together the leg members 2 are caused to bear with considerable force against each other. As shown in Fig. 2, the clothes pins may be split as at 8 so that two similarly molded halves may be brought together and vulcanized, glued, or otherwise secured to form a permanent clothes pin.

If, in forming the integral type of rubber clothes pin a greater resiliency is desired at

the mouth of the pin, suitable spring members 9 may be embedded in the pin when initially molded. Such spring members 9 may be joined in one piece, as best shown at 10, in 5 Fig. 3.

It will be understood that in addition to obtaining the novel practical results by forming the clothes pin of rubber, that the molding of this rubber permits of widely varying 10 shapes and designs of the clothes pin and in Fig. 4 I have illustrated one manner of molding a novelty rubber clothes pin. As rubber clothes pins are permanent and can be easily washed, it will be understood that the fact 15 that the pin may be molded into any suitable design or shape without any additional time or expense will prove a great advantage in this type of clothes pin. In addition to any ornamental or practical shape, it will be also 20 understood that the rubber may be given any color or combination of colors.

It will thus be seen that I have provided a clothes pin which can be readily and easily molded from relatively inexpensive grades of 25 rubber. Such rubber clothes pin is permanent, can be placed in the ordinary wash tub and boiled, and will never break. In addition to the resiliency obtained from the peculiar shape and arrangement of the legs or 30 tongue members the elasticity of the rubber itself provides a much better grip on the clothes. Furthermore, the rubber surface at the mouth of the clothes pin will securely and positively grip the clothes without any 35 harmful effect thereon and clearly there will be no tearing or ripping of the clothes as is a common result from wood clothes pins.

What I claim is:

1. As a new article of manufacture, a rubber clothes pin having downwardly extending 40 similarly shaped leg members with converging inner faces, said leg members being substantially in contact with each other at said converging faces, said leg members having 45 diverging end portions, and said leg members being normally spaced apart from their converging faces to their junction with the body 50 of the clothes pin, the space at said junction

constituting an opening of a size to receive a clothes-line.

2. A clothes pin of molded rubber comprising a body portion, a pair of legs extending from the body portion, said legs being spaced apart where they join the body portion to afford reception of the clothes line, said legs having inner faces which converge from the body portion throughout the greater portion of their length to a point substantially in contact with each other, said faces diverging from said point to the extreme ends of the legs, said body of molded rubber being self-sustaining and inherently providing gripping action of the legs for clothes or the like disposed between them.

3. A clothes pin of molded rubber comprising a body portion, a pair of legs extending from the body portion, said legs being spaced apart where they join the body portion to afford reception of a clothes line, said legs having inner faces which converge from the body portion throughout the greater portion of their length to a point substantially in contact with each other, said faces diverging from said point to the extreme ends of the legs, said body of molded rubber being self-sustaining and inherently providing gripping action of the legs for clothes or the like disposed between them, and a spring metal insert 55 in each leg for aiding the gripping action of the legs.

4. A clothes pin of molded rubber comprising two matching parts each with a half body portion with a leg extending therefrom, said half body portions being matched together and united to form a body portion, said legs having inner surfaces facing each other spaced apart where the legs join the body portion and converging throughout the greater length of the legs to a point of contact, said legs being held tensioned in contact with each other upon the uniting of the half body portions, said inner faces diverging from the point of contact to the extreme ends of the legs.

In testimony whereof I affix my signature.
LLOYD G. COPEMAN.
